UNITED STATES PATENT OFFICE

93,755

DESIGN FOR A HEATER

Max Arnold, New York, N. Y.

Application December 14, 1933, Serial No. 50,077

Term of patent 7 years

To all whom it may concern:

Be it known that I, MAX ARNOLD, a citizen of the United States, residing at New York city, county of Bronx, State of New York, have invented a new, original, and ornamental Design for a Heater, of which the following is a specification, reference being had to the accompanying drawing, forming a part thereof, and in which

Fig. 1 is a perspective view of a heater embodying my new design;

Fig. 2 is a top plan view of the heater; and Fig. 3 is a front elevation of the heater.

The dominant feature of the design resides in the appearance of the heater produced by the provision of the hinged curved plates upon the inner faces of the clamping jaws of the heater.

I claim:

The ornamental design for a heater as shown and described,

MAX ARNOLD.
